(57) CLAIM

I claim the ornamental design for a lacing guide, as shown and described.

DESCRIPTION

FIG. 1 is a first perspective view of a lacing guide, showing the top, a first end, and a first side of my new design; FIG. 2 is a second perspective view thereof, showing the top, a second end, and a second side;

FIG. 3 is a third perspective view thereof, showing the bottom, the second end, and the second side;

FIG. 4 is a view of the top thereof;

FIG. 5 is a view of the second side thereof, the first side being a mirror image of the second side; and, FIG. 6 is a view of the bottom thereof.
